UNITED STATES PATENT OFFICE.

EDWARD H. SCHEIFER, OF MIDVALE, IDAHO.

MULTIPLE CIRCULAR FILE.

1,288,218.

Specification of Letters Patent. Patented Dec. 17, 1918.

Application filed May 25, 1918. Serial No. 236,595.

To all whom it may concern:

Be it known that I, EDWARD H. SCHEIFER, citizen of France, residing at Midvale, in the county of Washington and State of Idaho, have invented new and useful Improvements in Multiple Circular Files, of which the following is a specification.

This invention relates to files, and more particularly to tools or implements of the character named, designed to be applied to a lathe chuck or other rotating member.

One object of the invention is to provide a plurality of disks each of which is serrated on the outer edge thereof in order to afford an abrasive surface, with means for assembling these disks in a series to form a single disk file, the outer element being employed at a given time as the abrasive tool.

A further object is to provide a disk having a serrated outer edge and if desired a roughened surface, adapted to be secured directly to a lathe chuck or the like, this disk being threaded on the edge for engaging complementary threads on the inner edge of an opening in a ring member constituting another abrasive element, the latter being provided with serrated portions on the edge and on the surface. An additional annular member formed as above indicated may surround the ring member first named and have threaded connection therewith.

With the foregoing and other objects in view, my invention consists in the novel construction, combination, and arrangement of elements hereinafter described and claimed.

In the drawings:

Figure 1 is a view in elevation.

Fig. 2 is a view in section.

Fig. 3 is a detached view, it being understood however, that additional ring members may be provided.

A disk member 10 is provided with a central aperture 12, in order that it may be connected with a lathe chuck or any other rotating element, and this member 10 is provided with serrated portions on the edge 13 and on one or both surfaces as shown at 14. Member 10 is also provided with a series of threads 15 on the edge thereof, these threads engaging complementary threads 16 on a

ring member 17 constituting an abrasive element of greater diameter.

Member 17 is provided with a roughened surface 18 and a roughened edge 19 and with threads 20, and ring member 25 is similarly formed.

It will be understood that these serrated surfaces may be differently scored in order to provide files of gradually decreasing 60 fineness, so that any type of implement required on the work under way will be immediately available. If any single element is unduly worn, it may be renewed without renewing the other elements of the series, it 65 merely being necessary to reassemble the parts. One object is to economize time by providing a number of files of different degrees of fineness in position to be immediately used, without the necessity of obtaining another file from the case or tool box.

What is claimed is:

1. In a device of the class described, a disk member carrying threads on the edge portion thereof, and being provided with a 75 serrated face portion, and a ring member having threaded connection with the disk and provided with serrations on the edge portion thereof.

2. In a device of the class described, a disk 80 provided with threads, and a plurality of rings carried by said disk, each of the rings being provided with serrated portions, the rings having threaded connection with each other and certain of the rings having threaded connection with the disk.

3. In a device of the class described, a file comprising a series of annular members having inter-engaging means formed on the edge portions thereof for connecting said 90 members, and having serrated portions formed thereon.

4. In a device of the class described, a file comprising a series of annular members having threaded connection with each other, 95 the threaded portions of certain of the members being intersected by transverse channels forming filing surfaces.

5. In a device of the class described, a plurality of annular members one of which 100 is provided with means for securing the

same to a rotating element, the others of said annular members having inter-engaging portions on the edges thereof and each of said members being provided with a serrated edge portion.

6. In a device of the class described, a plurality of annular members one of which constitutes a disk and is provided with a serrated and threaded edge portion, the second

of which is provided with threads engaging the threads of the disk and with a second series of threads; and the third of said annular members being provided with a series of threads engaging the threads of the second member and also provided with serrated portions on the outer edge thereof.

In testimony whereof I affix my signature.

EDWARD H. SCHEIFER.
